 corporation of Delaware

Application January 27, 1950, Serial No. 140,833

4 Claims. (Cl. 333—10)

1

This invention relates to electromagnetic energy couplers between ultra high frequency energy transmission lines, and in particular relates to directional couplers of the coaxial line type.

A directional coupler is a device which, when inserted in tandem in a transmission line on which there exists waves travelling in both directions, delivers to a pair of terminals located in an auxiliary transmission line a voltage which is largely a function of the amplitude of the wave travelling in one preferred direction in the main transmission line, and relatively independent of the wave going in the opposite direction.

That part of the directional coupler which is inserted in tandem with the transmission line is called the primary or main line. It possesses a set of main line input terminals at which the wave travelling in the preferred direction enters. The other set of terminals is called the main line output terminals.

The secondary or auxiliary line has, in addition to its output terminals, a termination element. This element serves to absorb the energy coupled into the auxiliary line which is travelling in the "wrong" direction and further serves to provide a good impedance match when looking into the auxiliary line from its output terminals. The main and auxiliary lines are connected together by a coupling mechanism which gives the coupler its directive properties.

The operation of a directional coupler may be described in terms of its coupling, directivity, and band width. The coupling specifies that fraction of the power proceeding in the preferred direction in the main line which is delivered to the auxiliary line output terminals. More precisely, the coupling, which may be expressed either as a voltage or power ratio, is defined as the ratio of voltage (or power) delivered to a matched detector at the auxiliary line output terminals to the voltage (or power) delivered to the coupler's main line input terminals, provided the main line output terminals are terminated in a matched load.

The directivity of a directional coupler is the ratio of voltage (or power) delivered to the termination element in the auxiliary line to the voltage (or power) delivered to the matched detector in the auxiliary line when power is flowing in the main line in the preferred direction with a matched load connected to the main line output terminals. Conventionally, this ratio is expressed in decibel notation.

The band width of a directional coupler may be defined as the frequency operating range over

2

which a directional coupler maintains a preassigned minimum directivity and coupling. In an ideal directional coupler the directivity and coupling are independent of the operation frequency.

One type of directional coupler well known in the art is the Bethe hole coupler. Such a coupler consists of two sections of transmission line, such as coaxial line, having a common outer conductor wall section. The coupling mechanism consists of a small aperture in this common wall section. The coupling mechanism of an ideal Bethe hole coupler may be explained as follows:

A small, round hole, connecting two parallel coaxial transmission lines will, when excited by constant field, such as that of the TEM mode of coaxial propagation, excite energy flow in the secondary or the auxiliary line. In particular, for energy travelling in the forward direction in the primary or main line, such a hole will cause some energy to travel equally in both directions in the secondary line, due to excitation of the hole by the electrical component of the TEM mode. Simultaneously, four times the above energy (twice the amplitude) will flow only in the reverse direction in the secondary line due to excitation of the magnetic component of the TEM mode. In order to achieve good directivity (a minimum of energy travelling in the forward direction of the auxiliary line) the primary and secondary lines are inclined at an angle of approximately 60°. This inclination will have no effect on the electric excitation of the hole since the electric field is perpendicular to it; however, it will decrease the amplitude of magnetic excitation by the cosine of the angle of inclination. Thus, for 60 degrees inclination the amplitude of energy excited by the magnetic field will equal the amplitude of energy excited by the electric field, resulting in amplitude cancellation in the forward direction and amplitude addition in the backward direction.

In many applications it is undesirable to have the main and auxiliary line sections oriented at an angle to each other. Instead, it is usually preferred to have them positioned parallel to each other. Bethe has shown that, theoretically, such a parallel line directional coupler is possible to design if the coupling aperture is a thin slot, infinite in length instead of the finite circular aperture described above. In such a thin slot type coupling aperture the magnetic and electric couplings are equal in amplitude and the desired directivity is achieved without the necessity of adjusting the angle between the main and auxiliary lines. However, by making the slot very thin

the coupling is extremely low. Furthermore, in practice, a thin slot which is infinite in length is impossible to achieve.

It is therefore an object of the present invention to provide a coaxial type directional coupler whose line sections are oriented parallel to each other.

It is another object of the present invention to provide an axial-slot type directional coupler having a relatively large coupling while maintaining frequency insensitive directivity.

It is a further object of the present invention to provide an axial-slot type directional coupler having a relatively large coupling while introducing a minimum amount of reflection in the main and auxiliary lines.

Yet, another object of the present invention is to provide a closely coupled, axial-slot type directional coupler in which the ratio of the induced electric and magnetic fields is substantially constant and unity regardless of the frequency within the operating range.

Another object of the present invention is to provide means for compensating the limiting effects of a finite length coupling slot in an axial-slot type directional coupler.

Still another object of the present invention is to provide means for increasing the electric coupling between the main and auxiliary line sections of a coaxial line type directional coupler.

A further object of the present invention is to provide an axial-slot type directional coupler having a relatively large coupling while maintaining the characteristic impedance of the main line constant.

In accordance with the present invention, a directional coupler of the coaxial line type is provided having its main and auxiliary line sections oriented parallel to each other with the inner or outer conductor of the main line having a common wall section with the inner or outer conductor of the auxiliary line. Coupling is provided by means of a long, thin slot in the common wall section. A raised, conductive section is provided along the inner conductor in order to compensate for the limiting effects due to the finite length of the slot. In addition, the raised section aids in maintaining the original characteristic impedance of the main coaxial transmission line constant, thereby minimizing the standing wave ratio therein.

These and other features of the present invention will become apparent from a consideration of the following specification and attached drawings, wherein:

Fig. 1 shows a sectional view of a coaxial line type directional coupler utilizing one embodiment of the present invention;

Fig. 2 is a cross-sectional view taken along the line 2-2 of Fig. 1;

Figs. 3 and 4 are schematic representations of the present invention useful in describing its operation more fully;

Fig. 5 is a sectional view of another coaxial line type directional coupler utilizing the features of the present invention in both the main and auxiliary line sections;

Fig. 6 is a cross-sectional view taken along the line 6-6 of Fig. 5;

Fig. 7 is a sectional view of another coaxial line type directional coupler utilizing the features of the present invention; and

Fig. 8 is a cross-sectional view taken along the line 8-8 of Fig. 7.

Referring now particularly to Fig. 1, there is

shown coaxial line section 10 having inner conductor 11 and outer conductor 12 oriented parallel with coaxial line section 14 having inner conductor 15 and outer conductor 16. Outer conductors 12 and 16 are contiguous, forming a common wall section between coaxial line sections 10 and 14. Coupling between line sections 10 and 14 is achieved by means of an axially directed slot 20 positioned in the common wall section formed by outer conductors 12 and 16. This slot 20 is directed along the axis of coaxial lines 10 and 14 and has a finite length-to-width ratio. A bar providing a conductive ridge 21 is mounted on inner conductor 11 along the length of slot 20. This conductive ridge 21 extends in a direction toward slot 20 as is seen more fully in Fig. 2 which is a section view taken along line 2-2 of Fig. 1. Tapered sections 22 and 23 are provided at each end of conductive ridge 21 in order to minimize any reflections created in main transmission line 10 thereby.

In operation, axially directed slot 20 couples energy from main line section 10 to auxiliary line section 14. By virtue of its finite length-to-width ratio the coupling therethrough is predominantly magnetic. In order for the coupler to achieve a high degree of directivity, it is essential that the electric and magnetic couplings be made equal to each other. By decreasing the width of slot 20 the amount of magnetic coupling is reduced more rapidly than the amount of electric coupling. In fact, as mentioned above, Bethe has shown that if the length-to-width ratio were infinite the electric and magnetic couplings would be equal. Reducing the width of the coupling slot, however, reduces the overall coupling between lines 12 and 14. In many cases it is desirable to provide the maximum amount of coupling possible while still providing a high degree of directivity. To achieve this result, the conductive ridge 21 is added in accordance with the present invention. This conductive ridge reduces the effect of distance between the inner conductor 11 of coaxial line section 10 and the inner conductor 15 of coaxial line section 14. This results in an increase of electric field strength in the region of axial slot 20 and thereby increases the electric field coupling between line sections 10 and 14. If conductive ridge 21 is properly dimensioned this increase in electric field coupling results in an equal amount of electric and magnetic coupling between line sections 10 and 14 thereby resulting in high directivity. In practice the width 55 of the ridge 21, i. e., the dimension measured transversely of the plane defined by the parallel longitudinal axes of the coaxial line sections, is made less than the diameters of the inner conductors 11 and 15 in contrast to the width of the coupling slot 20, which is greater than the diameters of the inner conductors. It should be noted that this desirable result is achieved without reducing the overall coupling between the two coaxial line sections.

As might be expected, any opening in the outer conductor 12 of transmission line section 10, such as is provided by slot 20, tends to raise the characteristic impedance of the transmission line in the region of the coupling aperture. This, of course, is due to the increase in the equivalent diameter of the outer conductor in this region. Naturally, any change in the characteristic impedance produces a discontinuity in the transmission line with the result that energy reflections are set up at the point of the dis-

continuity. Such energy reflections create a large standing wave ratio with its resulting low efficiency and decrease in power handling capabilities.

By introducing the conductive ridge 21 in the region of axial slot 20 the effective diameter of the inner conductor is also increased. This, of course, tends to make the characteristic impedance of the transmission line constant. Figs. 3 and 4 aid in showing that, not only does the conductive ridge aid in equalizing the electric and magnetic coupling, but at the same time increases the effective diameter of the inner conductor sufficiently to make the characteristic impedance of the main transmission line constant.

Fig. 3 is a schematic representation of the lumped constant equivalent circuit for a coupler employing both electric and magnetic coupling. The equivalent circuit is shown on a normalized basis. Alternating current generator 30, having internal impedance 31 is connected to the input terminals 32 and 33 of main transmission line 34. This transmission line is terminated with impedance 35. Auxiliary line 40 is coupled both electrically and magnetically to main transmission line 34. The series inductance of the coupling aperture is represented by inductor 41 and the shunt capacity is represented by capacitor 42. Auxiliary transmission line 40 is terminated by impedances 43 and 44.

The circuit shown in Fig. 3 can be transformed into a bridge circuit as shown in Fig. 4. It is evident from this representation that if the inductance of inductor 41 is equal to the capacity of capacitor 42 (on a normalized basis), no current will flow in resistor 44, which represents the termination of the auxiliary line section 40. It should be remembered that this is the condition for infinite directivity since by definition directivity is the ratio expressed in decibels of voltage delivered to a termination element (resistor 44) in the auxiliary line 40 to the voltage delivered to the matched detector (resistor 43) in the auxiliary line 40 when power is flowing in the main line 34 with a matched load (resistor 35) connected to the main line output terminals. Thus, if no current flows in resistor 44, by definition, the directivity is infinite. It should be noted that this condition is independent of frequency.

Coincident with this directive property of this four-terminal network is the fact that the balanced bridge condition presents a matched impedance to the source as measured across terminals 32, 33. Thus, the lumped constant analysis leads to the conclusion that the highest intrinsic directivity and a good match of the coupling element to the primary line will exist coincident with each other. It is thus apparent that the excessive magnetic coupling caused by the finite length-to-width ratio of the coupling slot is equivalent to the fact that the inductance of inductor 41 is greater than the capacity of capacitor 42. By adding the proper amount of capacity to the system at the point of coupling the bridge is balanced. This additional capacity, in accordance with the present invention, results from the insertion of the raised section or conductive ridge 21 along the inner conductor 61 of main line 10.

While the embodiment of the present invention illustrated in Figs. 1 and 2, show the conductive ridge employed in the main line only, Fig. 5 illustrates another embodiment of the present

invention in which the conductive ridge is employed in both the main and auxiliary line sections. Reference to Fig. 5 shows main transmission line 60 having inner conductor 61 and outer conductor 62 oriented parallel to auxiliary transmission line 64 having inner conductor 65 and outer conductor 66. Outer conductors 62 and 66 are contiguous, forming a common wall section between coaxial line sections 60 and 64. Coupling between the line sections 60 and 64 is achieved by means of an axially directed slot 70 positioned in the common wall section formed by outer conductors 62 and 66. Main transmission line 60 is terminated at one end in a conventional male coupling 100 to which a matched resistor 105 is shown connected schematically. The opposite end is terminated in a conventional female coupling 101 to which generator 106 with internal impedance 107 is shown connected schematically.

As in the previous embodiment, this slot 70 is directed along the axis of main line 60 and auxiliary line 64 and has a finite length-to-width ratio. One end of auxiliary line section 64 is terminated in matched impedance element 71. This terminating element serves to absorb any incident energy thereon preventing reflections in line section 64. The opposite end of auxiliary line section 64 is provided with a right angle section 72 which is terminated in a conventional male output coupling 102 to which a matched load 73 is shown connected schematically.

Conductive ridge 81 is mounted on the inner conductor 61 along the length of slot 70. This conductive ridge 81 extends in a direction toward slot 70 as is seen more fully in Fig. 6 which is a section view taken along line 6-6 of Fig. 5. Tapered sections 82 and 83 are provided at each end of conductive ridge 81 in order to minimize any reflections created due to an impedance discontinuity caused by the presence of element 81 in main transmission line 60. Conductive ridge 91 is mounted on inner conductor 65 along the length of slot 70. This ridge 91 also extends in a direction toward slot 70. Tapered sections 92 and 93 are provided at each end of this ridge element in order to minimize reflections in auxiliary line 64.

As in the previous embodiment, axially directed slot 70 couples energy from main line section 60 to auxiliary line section 64. This coupling is predominantly magnetic due to the finite length-to-width ratio of the long, thin axial slot type coupling aperture. Conductive ridges 81 and 91 serve to increase the electric field strength in the region of the coupling aperture, and thereby increase the amount of electric coupling. This enables the overall electric coupling to equal the magnetic coupling thereby achieving a high degree of directivity. This high directivity is achieved without reducing the amount of magnetic coupling resulting from slot 70, thereby permitting the overall coupling to remain relatively large. As discussed above, the conductive ridges also tend to increase the effective diameter of the inner conductors in the region of the coupling slot. This offsets the increase in effective diameter of the outer conductor due to the coupling slot, maintaining constant characteristic impedance in the main and auxiliary transmission lines. This, of course, results in a smooth flow of energy with a minimum amount of reflection introduced by the coupling mechanism. As shown above, this desirable result is achieved by virtue of com-

pensating elements 81 and 91, their compensating effects being independent of operating frequency.

Fig. 7 illustrates another form of a coaxial line type directional coupler utilizing the present invention. In this embodiment coaxial line section 110 is formed of inner conductor 112 and conductor 113. Coaxial line section 114 utilizes conductor 113 as its inner conductor and outer conductor 115. Thus, conductor 113 forms a common wall between nested coaxial line sections 110 and 114. An axially directed coupling slot 120 is formed in the common wall 113. Conductive ridge 121 is mounted on inner conductor 112 along the length of slot 120, and has tapered sections 122 and 123 at each end thereof. Generator 130 having internal impedance 131 is shown connected schematically to one end of coaxial line section 110, and termination element 132 is shown connected to the opposite end thereof. Termination elements 133 and 134 are shown connected to opposite ends of coaxial line section 114.

The relative positioning of these elements is better seen in Fig. 8 which is a cross-sectional view taken along line 8-8 of Fig. 7. This figure not only shows the nested relationship of conductors 112, 113 and 115, but shows conductive ridge 121 extending radially outward from inner conductor 112 toward coupling slot 120.

As in the previous embodiments a portion of the energy introduced into coaxial line section 110 by generator 130 is coupled into coaxial line section 114 by coupling aperture 120. Because of the finite length-to-width ratio of the aperture 120 more magnetic coupling is achieved than electric coupling. Conductive ridge 121 overcomes this difficulty by introducing an additional amount of electric coupling, thereby permitting a high degree of directivity.

Although only a single conductive ridge is shown in the embodiment of Fig. 7, it is understood that an additional ridge mounted on the outer conductor 115 could also be utilized as in Fig. 5.

It is thus seen by the introduction of compensating elements in a coaxial line type directional coupler whose main and auxiliary lines are oriented parallel and whose coupling is provided by an axially directed slot, high directivity may be achieved over large frequency operating ranges. In addition, such compensating elements permit relatively large coupling between the main and auxiliary transmission lines. Not only do these compensating elements increase the amount of electric coupling thereby providing a high degree of directivity, but they serve to maintain the characteristic impedance of both the main and auxiliary transmission lines constant, thereby minimizing any energy reflections introduced by the coupling aperture.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An ultra-high-frequency directional coupler comprising a first section of coaxial transmission line having an inner and outer conductor, a second section of coaxial transmission line having an inner and outer conductor, said second section

being oriented parallel to said first section and having a common outer conductor wall section therewith, said common wall section having an axially directed coupling slot located therein, and a first thin conductive strip of width substantially less than the diameters of said inner conductors secured along one edge to the inner conductor of said first section, said strip extending longitudinally along the inner conductor opposite the coupling slot, a second thin conductive strip of width substantially less than the diameters of said inner conductors secured along one edge to the inner conductor of said second section, said second strip extending longitudinally along the inner conductor of said second section opposite the coupling slot, said strips projecting radially toward each other, the ends of said strips being tapered, the width of said coupling slot being greater than the diameters of said inner conductors.

2. An ultra-high-frequency directional coupler comprising a first section of coaxial transmission line having an inner and outer conductor, a second section of coaxial transmission line having an inner and outer conductor, said second section being oriented parallel to said first section and having a common outer conductor wall section therewith, said common wall section having an axially directed coupling slot located therein, and a first thin conductive strip of width substantially less than the diameters of said inner conductors secured along one edge to the inner conductor of said first section, said strip extending longitudinally along the inner conductor opposite the coupling slot, a second thin conductive strip of width substantially less than the diameters of said inner conductors secured along one edge to the inner conductor of said second section, said second strip extending longitudinally along the inner conductor of said second section opposite the coupling slot, said strips projecting radially toward each other, the ends of said strips being tapered, the width of said coupling slot being substantially greater than the thickness of each of said strips.

3. An ultra-high-frequency directional coupler of the coaxial transmission line type comprising a first section of coaxial transmission line having an inner and outer conductor, a second section of coaxial transmission line having an inner and outer conductor, said second section being oriented parallel to the first section and having a common outer conductor wall section therewith, said common wall section having an axially directed coupling slot located therein, the width of said coupling slot being greater than the diameters of said inner conductors, and a thin conductive bar secured along one edge to the inner conductor of said first section of coaxial line opposite the coupling slot and projecting radially toward the slot substantially in the plane defined by the parallel inner conductors of said coaxial sections, the bar having a width less than the diameters of said inner conductors.

4. An ultra-high-frequency directional coupler comprising a first section of coaxial transmission line having an inner and outer conductor, a second section of coaxial transmission line having an inner and outer conductor, said second section being oriented parallel to said first section and having a common outer conductor wall section therewith, said common wall section having an axially directed coupling slot therein, the width of said coupling slot being greater than the diameters of said inner conductors, a first thin

conductive strip of width less than the diameters of said inner conductors secured along one edge to the inner conductor of said first section, said strip extending longitudinally along the inner conductor opposite the coupling slot, and a second thin conductive strip of width less than the diameters of said inner conductors secured along one edge to the inner conductor of said second section, said second strip extending longitudinally along the inner conductor of said second section opposite the coupling slot, said strips projecting radially toward each other.
